UNITED STATES PATENT OFFICE.

MERRILL MOORE, OF CRESTON, IOWA.

DEVICE FOR MOLDING CONCRETE SLABS OR BLOCKS.

1,219,131.

Specification of Letters Patent. Patented Mar. 13, 1917.

Application filed May 31, 1916. Serial No. 100,785.

To all whom it may concern:

Be it known that I, MERRILL MOORE, a citizen of the United States, residing at Creston, in the county of Union and State 5 of Iowa, have invented certain new and useful Improvements in Devices for Molding Concrete Slabs or Blocks, of which the following is a specification.

This invention relates to molds for producing concrete slabs or building blocks and is especially designed to provide a mold which may be readily assembled into a suitable series of molds, and the removable parts easily and quickly disassembled to remove therefrom the molded products.

The prime object of my invention is to provide a simple, economical, durable, and thoroughly efficient device for producing a concrete slab or block having embedded 20 therein a metal reinforcement which also serves as a means for tying or bonding the said slabs or blocks together.

Another object of this invention is to mold or cast a series of concrete slabs or blocks 25 on end at the same time, in a single structure, which includes a series or any suitable or desirable number of molds combined together and firmly secured so that the entire series of molds may be handled as a unitary 30 device.

A further object of the invention is to provide a novel device which will form building slabs of uniform thickness at their central or body portion and at each side 35 thereof will be formed a reduced extension of only one half the thickness of said central or body portion, each slab or block having embedded cross-wise therein in an inclined position, two reinforcing rods, each 40 rod having a loop or eye formed at either end thereof and terminating within the reduced extended portion at each side of the block.

A still further object of the invention is 45 to provide a simple device constituting a series of molds secured together by means which hold the reinforcing rods in the slabs in their proper position, said means passing through each slab and each loop or eye 50 forming a part of the reinforcement, thereby forming a part of the reinforcement, thereby forming a hole through the slab at four different points, through which holes bolts or pins are used for fastening the slabs together during the process of constructing a 55 building with the said slabs.

The foregoing and such other objects as may appear from the ensuing description are attained by the novel features of construction, combination, arrangement and location of the parts, hereinafter fully described, illustrated in the accompanying drawings, and particularly pointed out in the claims appended hereto, it being understood that slight changes in the form, proportions, and minor details of the construction may be resorted to without departing from the spirit or sacrificing any of the advantages of the invention.

In the accompanying drawings it will be seen that:

Fig. 1, is a perspective view showing the improved device embodying my invention.

Fig. 2, is a plan view of the same.

Fig. 3, is a transverse sectional view, taken 75 on the line *a—a*, Fig. 1.

Fig. 4, is a sectional elevation of the same, taken on the line *b—b*, Fig. 2.

Fig. 5, is a perspective view showing a series of the slabs with means for tying or 30 binding them together shown by dotted lines.

Similar numerals of reference are employed to designate corresponding parts throughout the several figures of the drawings.

In carrying out my invention as illustrated and which shows a preferred construction, Figs. 1, 2, 3 and 4 show a series of three molds united together in a single 90 structure, but it will be understood that any suitable number of molds may be assembled together, which may be readily handled by the manipulator of the molding process.

Having reference to the drawings, the numeral 1 indicates a plate of sheet metal secured in a vertical position forming one end of the mold structure, 2 is a corresponding plate secured in a vertical position forming or constituting the other end of the 100 structure, while 3 and 4 designate division or partition plates, all of said plates being of the same material, positioned vertically, and secured at any suitable distance apart dependent upon the thickness of the slab it 105 is desired to mold.

Rigidly secured between the vertical plates, at a point near the outer edge or side portion thereof is a vertical sheet metal member 5, forming one of the side walls 110

of each mold in the series, each of said metal members 5, being formed with an outward lateral extension 6, an upright portion 7 adapted to form the upper and outer side face of the slab, a central lateral outward extension 8, and an upright portion 9 for forming the lower and outer side face of the slab, and constituting the other or opposite side wall of each mold is rigidly secured 10 a vertical sheet metal member 10, each of said metal members 10, having an outer upright portion 11 adapted to form the upper and outer side face or edge of the slab, a lateral central inward extension 12, an upright portion 13, for forming the lower and outer face or edge of the slab, and a lateral outward extension 14.

It will be readily seen by reference to the drawings that the lateral extension 6 of each member 5, and the lateral extension 14 of each member 10, rest in contact with one of the vertical plates and are firmly secured thereto by a plurality of rivets 15, while the free edge of the upright portion 9, of each member 5, and the free edge of upright portion 11, of each member 10, also contact with one of the vertical plates, and that by forming said members 5 and 10, in the manner hereinbefore described, each molded slab is formed with an extension at either side thereof, one projecting from its upper or face portion and the other from its lower or bottom portion.

Within each mold is placed at a point about one-fourth the length of the mold from each end, a reinforcing rod or bar 16 provided at each end thereof with an integral loop or eye 16', each of said rods or bars being supported in an inclined position, the eye or loop at one end of the rod terminating within the upper lateral extension 17 formed in each mold, and the eye or loop at the other end of the bar terminating in the lower lateral extension 18 formed in each mold.

Passing entirely through the series of molds are four rods 19, screw-threaded at each end thereof, adapted to receive a securing nut 20 at each end of the rods, said rods being utilized for securely clamping the molds together, and are so positioned, two at each side of the series of molds, that they hold and support the reinforcing rods or bars 16 in their proper inclined position, 55 pass through the eye or loop in the reinforcing rod thereby forming a hole through the slab at this point, the two bolts at one end of the mold passing through upper extensions 17 formed in one side of each mold, and the two bolts at the other side passing through the lower extension 18, thus forming two holes through each slab extension, each of said holes being adapted to receive a bolt or pin 21 used to fasten or tie the slabs together when constructing a building, since each of said fastening bolts or pins is intended to pass through a hole in the upper lateral extension and through the eye or loop of the reinforcing rod in one slab, and through the hole and the eye or loop of the reinforcing rod in the lower lateral extension of the next adjacent slab, thereby fastening or tying the building slabs together.

It will be understood that the slabs may be utilized in the construction of both straight and circular walls in the process of building.

Having thus described my invention what I claim and desire to secure by Letters Patent is:—

1. A device for molding building slabs, comprising a series of vertical plates, a series of vertical side walls secured to said vertical plates, said side walls forming an upper and lower lateral molding chamber extension between each vertical plate, and a plurality of rods passing through each vertical plate and through part of the molding chamber, forming a hole in the slab, and clamping the mold elements together. 80

2. A device for molding building slabs, comprising a series of molds formed by a series of vertical plates, a series of vertical side walls secured to said vertical plates, said side walls being constructed so as to form an upper and a lower lateral molding chamber extension within each mold, a plurality of rods passing through the said vertical plates, through part of the molding chamber, forming a hole in the slab, and clamping the mold elements together, and 95 means for securing each rod at each end thereof. 100

3. A device for molding building slabs, comprising a series of molds formed by a series of vertical plates, a series of vertical side walls secured to the vertical plates, and a plurality of rods passing through the said vertical plates and through part of the molding chamber, forming a hole in the slab, and clamping the mold elements together, said rods serving to support a plurality of reinforcing bars within each mold. 110

4. A device for molding building slabs, comprising a series of molds formed by a series of vertical plates, a series of vertical side walls secured to said vertical plates, said side walls forming an upper and lower lateral molding chamber extension within each mold, a plurality of rods passing through the said vertical plates and through part of the molding chamber, forming a hole in the slab, and clamping the mold elements together, said rods serving to support a plurality of reinforcing rods within each mold, and means for securing the rods at 120 each end thereof. 125

5. A structure for molding building slabs, comprising a series of vertical plates, a series

of vertical side walls secured to said plates, each side wall consisting of two lateral extensions and two upright walls at a right angle to said lateral extensions adapted to 5 form extended molding chambers, a plurality of rods passing through the said vertical plates and through part of the molding

chamber, forming a hole in the slab, and clamping the mold elements together, said rods serving to support a plurality of reinforcing rods within each mold, and means for securing the rods at each end thereof. 10

MERRILL MOORE.
